UNITED STATES PATENT OFFICE.

OSCAR COSSERAT, OF AMIENS, FRANCE.

MECHANISM FOR CHANGING THE SHUTTLES IN LOOMS.

SPECIFICATION forming part of Letters Patent No. 793,278, dated June 27, 1905.

Application filed March 4, 1904. Serial No. 196,532.

To all whom it may concern:

Be it known that I, OSCAR COSSERAT, a citizen of the Republic of France, and a resident of Amiens, France, have invented new and useful Improvements in or Relating to Mechanism for Changing the Shuttles in Looms, which improvements are fully set forth in the following specification.

This invention relates to improvements for the purpose of rendering possible the changing of shuttles in "whipping" or overpick looms in the apparatus for automatically changing the shuttles in looms, which forms the subject of a former United States patent, No. 787,497, dated April 18, 1905.

The mechanism described and illustrated in the said patent, enables the changing of a shuttle to be effected by a succession of the following operations: first, stoppage of the loom in a given position; second, shifting one of the shuttle-boxes of the loom; third, replacing the empty shuttle by a full one; fourth, restarting the loom. It would be superfluous to repeat here the description of the above four operations. It is sufficient in order to make the explanation hereinafter quite clear to recapitulate the way in which the second operation takes place in the case of a "sword" or underpick loom.

It has been explained in the previous patent that the two parallel rods supporting the box form a portion of the slay or "going part" of the loom and oscillate with it and that besides those two parallel rods raise only the portion of the box containing the shuttle, leaving at the end of the slay the picker of the loom, which remains in place during the ascent of the box. As soon as the box has risen above the picker it is opened at both ends, thereby enabling the shuttles to be freely introduced and withdrawn. That is the way in which the second operation takes place in the case of an underpick-loom; but in the case of an overpick-loom a slight modification must be made in the loom, as its picker is no longer the same. It is necessary, in fact, that the picker should not be raised with the box, in order that the latter after having arrived at the level of the shuttle receptacle or store

should remain open at both ends; but in the "overpick-loom" the picker forms, so to say, part of the box, as it is guided in its rectilinear movement by a rod passing through it and secured to the box of the loom, so that the picker cannot be easily separated from the box.

In order to obviate the above drawback, the loom is modified, as shown by way of example in the accompanying drawings, in which—

Figure 1 is a side elevation of an overpick-loom provided with the improvements according to this invention. Fig. 2 is a side elevation of the same loom during the raising of the box.

The loom is provided, on the side only where the changing of the shuttles takes place, with a false sword or arm 15, which receives a picker 16, similar to that of a sword or underpick loom: this false sword is attached at the top to the picking-strap 17, which transmits motion to it. Owing to this addition, the working becomes absolutely the same as that of an underpick-loom. The portion 18 of the box containing the shuttle can be raised, leaving at the end of the going part the picker of the loom, which being held by the false sword remains in place in the fixed portion 19 of the box during the rising of the movable portion 18 of the box, all movements for the changing of the shuttle then taking place in the same manner as in an underpick-loom and as described in the above-mentioned patent.

I claim—

1. In shuttle-changing mechanism for whipping or overpick looms, the combination of a magazine containing weft, a shuttle-box formed in two parts, one fixed on the lay and the other adapted to be moved into relation with the magazine to receive a supply of weft therefrom, a picker adapted to remain in the fixed part of the box while the movable part is moved into relation with the magazine, a sword to which the picker is connected, and a connection to the upper end of the sword for imparting movement thereto.

2. In shuttle-changing mechanism for whipping or overpicking looms, the combination of a magazine containing weft, a shuttle-box

formed in two parts, one adapted to be moved into relation with the magazine to receive a supply of weft therefrom and in this moved position to be open at both ends, and the other fixed on the lay and adapted to close one end of the shuttle-box when the two parts are in position on the lay, a picker adapted to remain in the fixed part of the box while the movable part is moved into relation with the magazine, to a sword to which the picker is connected, and

a connection to the upper end of the sword for imparting movement thereto.

In testimony whereof I have signed this specification in the presence of two subscribing witnesses.

OSCAR COSSERAT.
